James E. Smith, INVENTORS.

BY David S. Lain,

ATTORNEY.

UNITED STATES PATENT OFFICE.

GEORGE V. NOLTE, OF BELLINGHAM, AND JAMES E. SMITH, OF BEACH, WASHINGTON.

IGNITION-PLUG.

1,293,520.

Specification of Letters Patent.

Patented Feb. 4, 1919.

Application filed July 26, 1918. Serial No. 246,845.

To all whom it may concern:

Be it known that we, GEORGE V. NOLTE, a citizen of the United States, residing at Bellingham, in the county of Whatcom and State of Washington, and JAMES E. SMITH, a citizen of the United States, residing at Beach, in the county of Whatcom and State of Washington, have invented a new and useful Ignition-Plug, of which the following is a specification.

Our invention relates to improvements in ignition plugs for use in interior combustion engines of the semi-Diesel type, which require the services of a plug for a few minutes at a time only to make a quick start; and the objects of our invention are: first, to provide an electrically-heated wire ignition plug the element of which, when not required in the operation of the engine, can be shielded from exposure to the rapidly moving gases within the cylinder; second, which can readily be removed and replaced during normal engine operation; and third, which is of a simple construction especially suited for small engines.

We have been granted Patent Number 1,249,465 on Dec. 11, 1917, for objects similar to the first two objects above stated and especially adapted to large engines.

We attain these objects with the mechanism illustrated in the accompanying drawing in which—

Figure 1 is a plan view of our plug shown in operative position and having certain parts broken away in order to show others hidden thereby, Fig. 2 is a front elevation of Fig. 1 in section on a longitudinal medial plane, Fig. 3 is a side elevation of Fig. 1, Fig. 4 is a side elevation of Fig. 1 having its entire upper portion broken away, and showing the parts in closed or non-operative position, Fig. 5 is a sectional view of Fig. 4 on a plane through line 10—10, Fig. 6 is a sectional view of Fig. 2 on a plane through line 9—9, and Fig. 7 is an elevation view of the electrode.

Similar characters refer to similar parts throughout.

More particularly: A is a portion of the cylinder cap in section. 1 is a hollow stud having a closed lower end protruding into the cylinder's interior. 1^a, 1^b are registering transverse holes through the walls of the lower end of stud 1 within the cylinder. 1^b

is a portion of the body of stud 1 threaded 33 to engage cylinder cap A. 1^c is the threaded upper and outer end of stud 1. 1^d is a hexagonal ring boss on stud 1 to provide a wrench hold. 1^e is a deep diametrical score on the upper side and edges of boss 1^d. 2 is 60 the metallic jacket of the electrode. 2^a is an insulating bushing in a counterbore in the lower end of jacket 2. 2^b is an insulating bushing in a counterbore in the upper end of the jacket 2 and extends above said jacket. 65 2^c is a circular nut on top of bushing 2^b. 2^d is a ring boss on jacket 2 near its upper end. 3 is the central rod of the electrode and has head 3^a on its lower end bearing against the lower end of bushing 2^b. The upper end of 70 rod 3 is threaded and on it is screwed nut 2^c to bear on the upper end of bushing 2^b. Also on this threaded end is screwed binding nut 3^b. 4 is the element, preferably made of refractory wire in the form of a helix. 75 One end of said wire is connected to rod head 3^a and the other end is connected to the lower end of jacket 2. 5 is the electrode cage and consists of a tube having a closed lower end and neatly fitted for revolution in 80 hollow stud 1. The lower end of cage 5 nearly reaches the bottom of said stud and has two registering holes 5^a, 5^b through its walls adapted to register with holes 1^a, 1^b when in the position in revolution illustrated 85 in Figs. 1, 2 and 6 but to be out of registry with said soles when turned through an angle of 90° to the position shown in Figs. 4 and 5. 5^b is a ring boss on cage 5 near its upper end adapted to bear on the upper end 90 of stud 1. 5^c is a threaded flange on the upper end of said cage with which hand wheel 5^e is engaged and more securely retained by pin 5^d. 5^f is a deep diametrical score across the top and sides of hand wheel 5^e which registers with score 1^e in boss 1^d when holes 5^a, 95 5^b register with holes 1^a, 1^b as shown in Figs. 1, 2, and 6; but is at right angles with said score when said holes are out of registry as shown in Figs. 4 and 5. 6 is a bushing nut 100 screwed into a tapped hole in the upper side of hand wheel 5^e and bears on ring boss 2^d. 7 is a gland nut engaged with the threaded end 1^c of stud 1 adapted to compress packing 8 on ring boss 5^b. 105 In operation, threaded body 1^b is engaged in a hole in cylinder A as shown only in Fig. 3, those parts of stud 1 below said

threaded body protruding within said cylinder while those parts above said threaded body extend outside of said cylinder. Cage 5 makes a turning fit in stud 1, and the joint 5 between the two is sealed by stuffing box nut 7 and packing 8 on ring boss 5^b. Jacket 2 makes a turning fit in cage 5, and the joint between the two is sealed by nut 6 clamping ring boss 2^d on flange 5^c. When 10 said nut 6 is tightly screwed down the electrode is turned with difficulty in the cage, but by easing said nut the electrode may be revolved freely. As noted, one end of element 4 is connected to rod 3, which is there- 15 fore insulated, while the other end of said element is connected to jacket 2 which connects it to the engine frame or "ground". One terminal, not shown, of a suitable source 20 of electricity, not shown, is connected under binding nut 3^b, while the other terminal of said source of electricity is connected to the engine frame as usual. The electric circuit of said source of electricity is supplied with a switch as usual. In starting 25 the engine this switch is closed and hand wheel 5^e is turned to cause score 5^f to register with score 1^e when holes 5^a, 5^a register with holes 1^a, 1^a, see Figs. 1, 2, 3 and 6, and element 4 is exposed to the gases in the engine 30 cylinder as described. But when the services of the hot element 4 are no longer required in the proper operation of the engine hand wheel 5^e is turned to cause score 5^f to be at right angles with score 1^e which 35 causes cage 5 to turn through an angle of 90° in stud 1 and holes 5^a, 5^a are turned out of registry with holes 1^a, 1^a, as shown in Figs. 4 and 5, and element 4 is shut off from exposure to the said cylinder gases. 40 When it is desired to remove electrode 2 during the operation of the engine the battery terminal under nut 3^b is removed, hand wheel 5^e is turned to cause score 5^f to be at right angles with score 1^e, nut 6 is unscrewed, when said electrode can be removed at pleasure. To replace said electrode the opposite order is followed. This mechanism is also suitable for use with a jump-spark element. 45 Having thus fully disclosed our invention

tion, what we claim as new and desire to secure by Letters Patent is—

1. In combination, the cylinder of an internal combustion engine, a hollow stud engaged in the walls of said engine cylinder 55 with its inner end protruding within the interior of said cylinder, and having two registering holes through its walls within said cylinder; an electrode cage mounted for revolution in said hollow stud having 60 two registering holes through the walls of its lower end, and adapted to be revolved to cause said holes to be in registry with said holes in said stud and also adapted to be turned to cause said holes to be out of 65 registry with said holes in said stud; and an electrode mounted in said cage having an element of refractory metal connected to its lower end adapted to hang between the holes in the lower end of said cage. 70

2. In combination, the cylinder of an internal combustion engine; a hollow stud engaged in the walls of said cylinder with its lower end closed and protruding into the interior of said cylinder and having 75 two registering holes through its walls within said cylinder, and also having a stuffing-box gland on its outer end without said cylinder; an electrode cage mounted for revolution in said hollow stud having two 80 registering holes through its lower end which are adapted to move into and out of registry with said holes in said stud when said cage is revolved, and also having a ring boss adapted to bear on the upper end of 85 said stud beneath the packing of said stuffing-box gland; an electrode mounted in said cage comprising a central metallic rod, an outer metallic jacket insulated from said rod and having a ring boss near its upper end; 90 a refractory wire one end of which is connected to the lower end of said rod and the other end of which is connected to the lower end of said jacket adapted to hang between the holes in said cage; and a bush 95 nut in the upper end of said electrode cage bearing on the ring boss on said electrode.

GEORGE V. NOLTE.
JAMES E. SMITH.
